(57) **CLAIM**

We claim the ornamental design for an electronic device holder, substantially as shown and described.

DESCRIPTION

FIG. 1 is a front perspective view of an electronic device holder in accordance with the present design.

FIG. 2 is a rear perspective view for the electronic device holder shown in FIG. 1.

FIG. 3 is a rear view for the electronic device holder shown in FIG. 1.

FIG. 4 is a front view for the electronic device holder shown in FIG. 1.

FIG. 5 is a bottom view for the electronic device holder shown in FIG. 1.

FIG. 6 is a top view for the electronic device holder shown in FIG. 1.

FIG. 7 is a right side view for the electronic device holder shown in FIG. 1; and,

FIG. 8 is a left side view for the electronic device holder shown in FIG. 1.
